MOLD DRAWING DEVICE FOR MOLDING MACHINES

Hans Jakob Rothschild, Schaffhausen, Switzerland, assignor to Georg Fischer Aktiengesellschaft, Schaffhausen, Switzerland, a company of Switzerland

Application February 10, 1949, Serial No. 75,703
In Switzerland December 9, 1948

2 Claims. (Cl. 22—48)

1

This invention relates to a mold drawing device for molding machines of the jolt, squeeze and draw type.

In operating molding machines of the above described type it is very important to control the speed of the drawing motion in such a way that at the very beginning and only over a short distance of the drawing motion the mold is drawn from the pattern at a very reduced speed, compared with the normal speed at which the operation is to be continued.

Molding machines with pneumatically actuated mold drawing devices are known. In these machines the controlling of the drawing speed is mostly accomplished by means of interchangeable cams or sliding crank blocks. The changing or altering of these regulating means is often complicated and time consuming.

The principal object of this invention is to provide regulating means for the drawing speed of the mold drawing cylinder by reducing the flow of a pressure medium through the bore of a vertically displaceable regulating means.

Another object of the invention is to provide means for altering the vertical position of the regulating means by means of a crank pin.

Another object of the invention is to provide check valve means in the vertically adjustable regulating means for controlling the drawing speed during the rising and lowering motion.

An embodiment of the molding machine according to the present invention is illustrated by way of an example in the accompanying drawing, in which

Fig. 1 is a vertical sectional view of the molding machine, a part thereof being shown in side elevation,

Fig. 2 is a sectional view of the regulating means; and

Fig. 3 is a detailed sectional view taken on the line II—II of Fig. 2.

In Fig. 1 are shown the molding machine standard 1, with the laterally rockable head piece 6, and the vertically adjustable press plate 5, the molding machine table 2 with the mold containing flask 3, and the pattern 4. With the mold drawing cylinder 7 are rigidly connected the supporting frame 8, the adjustable members 9 and the mold lifting pins 10. The mold drawing cylinder 7 is vertically slideable on the mold drawing piston 11 which is securely connected with the molding machine standard 1. Screwed into the upper end of the mold drawing piston 11 is the regulating pin 12, the diameter of which is slightly smaller than the diameter of the bore

2

33 in the regulating sleeve 14. The upper end of the regulating pin 12 may be pointed or conical. In the intermediate piece 20 between the two sections of the drawing cylinder 7 is the vertically 5 slideable regulating sleeve 14. Air supply conduit 17 leads into the pilot valve 18 and conduit 19 leads from the pilot valve 18 into the upper end of the space 13, which in service is to be filled with oil. The exhaust conduit 34 leads from the pilot valve 18 into the atmosphere. Rigidly connected with the machine standard 1 is the abutment 35 which serves as end stop for the maximum length of the drawing stroke.

In Figs. 2 and 3 are shown the details of the 15 regulating means. The intermediate piece 20 houses the axle 15 with the crank pin 21 which rests in the groove 22 of the regulating sleeve 14. On the axle 15 is the hand wheel axially slideable 20 16 with the key way 28 which serves as guide for the key 29 in the axle 15. The hand wheel 16 is pressed against the face 37 of the intermediate 25 piece 20 by means of the spring 27 which is secured to the axle 15 by means of the washer 25 and the nut 26.

The face 37 of the intermediate piece 20 is in 30 the above case provided with eight index holes 23 for the index pin 24 fixed in the hub of the hand wheel 16. The outside diameter of the hub of the handwheel 16 is fitted with a scale 36.

The regulating sleeve 14 has one bore 33 which 35 is slightly larger in diameter than the regulating pin 12. In the upper enlarged ends of two side bores 30 are check valve balls 31 which are secured in their bores by means of a securing wire 32.

The above described mold lifting device according to the Figs. 1, 2 and 3 operates as follows:

The Figs. 2 and 3 show the condition where the 40 crank pin 21 of the axle 15 rests in its lowermost position and where also accordingly the index pin 24 rests in the lowermost index hole 23 which is drawn hatched in Fig. 3. In this position of the crank pin 21 the regulating sleeve 14 rests also in its lowermost position where the distance up to which the regulating pin 12 enters into the bore 33 reaches its maximum.

For initiating the drawing operation, which 45 means the lifting-off of the mold 3 from the pattern 4, the pilot valve 18 is turned to such a position as to allow the air to enter from the supply conduit 17 through the conduit 19 into the upper end of the drawing cylinder 7. The whole space 13 which is not occupied by the drawing piston 11 is filled with oil. If compressed air is applied 50 on the surface of the oil level in space 13 then

the oil is forced downwards from the space 13 through the annular passage which is formed by the clearance between the regulating pin 12 and the bore 33 in the regulating sleeve 14. The oil is forced to flow only through this annular passage as the two side bores 30 remain closed because of the check valve balls 31 which do not allow the flow of oil in downwards direction. Due to the very limited area of said annular passage, the initial drawing speed will be very reduced as long as the regulating pin 12 projects into the bore 33. As soon as the regulating sleeve 14 has reached such a height above the drawing piston 11 that the regulating pin 12 leaves the bore 33, then the reduced initial drawing speed changes to a regular drawing speed, which is maintained until the drawing piston 7 touches the abutment 35.

When the drawing operation is completed, which means, that the mold 3 has been taken away from the lifting pins 10, then the pilot valve 18 is turned to such a position as to allow the air from the space 13 and the conduit 19 to be exhausted through the conduit 34 into the atmosphere. By their own weight the drawing cylinder 7, together with the parts 8, 9 and 10 begin to descend and this descending movement keeps on until the drawing cylinder 7 has reached its lowermost position, as indicated in Figs. 1 and 2. During this descending movement the oil in the drawing cylinder 7 rises from the lower space above the drawing piston 11 through the bore 33 as well as through the two side bores 30 of the regulating sleeve 14 into the upper space 13. By the flowing oil the check valve balls 31 in the side bores 30 are lifted until they touch the securing wire 32. Because of the fact that the oil is flowing through all three bores, 30 and 33, of the regulating sleeve 14, the descending speed of the drawing cylinder 7 exceeds the maximum speed of the ascending motion of said drawing cylinder.

If it is desirable to change the length of time during which the drawing speed is to be reduced before assuming its normal drawing speed, the following is done:

The hand wheel 16 with the index pin 24 is pulled away from the face 37 against the pressure of the spring 27 until the index pin 24 stays outside of its index hole 23. Now the hand wheel 16 is turned to such an extent that the index pin 24 rests above one of the other index holes 23. As soon as the handwheel 16 is released the index pin 24, by action of the spring 27, enters into this new index hole. This positioning of the hand wheel 16 may be accomplished by observing the graduation 36 on the hub of the hand wheel 16. The key 29 in the axle 15 is slideable in the keyway 28 of the hand wheel 16 and when the latter is turned the axle 15 with the crank pin 21 is turned as well. By the movement of the crank pin 21, which rests in the annular groove 22 of the regulating sleeve 14, the latter is moved vertically, i. e. the regulating pin 12 enters to a lesser depth into the bore 33 of the regulating sleeve 14. In a subsequent drawing operation the length of time during which the reduced initial drawing speed is maintained

will be shorter than in the previous setting of the regulating sleeve 14.

The utilization of a mold drawing device, according to the above described invention, allows the regulation of the initial drawing speed in a simple and accurate manner without interrupting the operation of the molding machine. This can be accomplished irrespective of the weight and form of the mold.

The end of the regulating pin may be conical in order to obtain a smooth and shockless change-over from the reduced initial drawing speed to the normal drawing speed.

I claim:

1. In a molding machine of the jolt, squeeze and draw type, a drawing device comprising, in combination with a molding machine standard, a lifting piston firmly connected with said standard, a drawing cylinder enclosing said piston and vertically slideable thereon, and pin-supporting means connected to said cylinder and movable therewith; a regulating sleeve located within said cylinder and having a bore passage formed therein, a regulating pin carried by said piston and entering said bore passage in the lowermost position of said cylinder, and means connecting said sleeve with said cylinder and selectively shifting said sleeve into one of a plurality of vertically displaced positions.

2. In a molding machine of the jolt, squeeze and draw type, a drawing device comprising, in combination with a molding machine standard, a lifting piston firmly connected with said standard, a drawing cylinder enclosing said piston and vertically slideable thereon, and pin-supporting means connected to said cylinder and movable therewith; a regulating sleeve located within said cylinder and having a bore passage formed therein, a regulating pin carried by said piston and entering said bore passage in the lowermost position of said cylinder, said sleeve having a groove formed therein, a crank pin located in said groove, an axle carrying said crank pin, a hand wheel axially slideable upon said axle and rotatable therewith, an intermediate piece carried by said cylinder and having a plurality of index holes formed therein, and means connected with said hand wheel for selectively engaging one of said index holes, whereby the turning of said hand wheel shifts said sleeve into one of a plurality of vertically displaced positions.

HANS JAKOB ROTHSCHILD.
